ABSTRACT: In a continuous-casting machine the guide rolls, which conduct the solidifying slab from the mold to the pinch rolls, conventionally are all idlers. The invention incorporates two sets of power-driven rolls among the guide rolls. The power-driven guide rolls, in conjunction with the usual power-driven pinch rolls below, control the forces on the descending slab and its movement as it solidifies.

GUIDE-ROLL ARRANGEMENT FOR CONTINUOUS CASTING

This invention relates to an improved guide-roll arrangement for a continuous-casting machine, and to a method of controlling forces on a continuously cast slab.

The form of continuous-casting machine in which my guide-roll arrangement and method are used includes a water-cooled mold open at both ends, trains of vertically spaced opposed pairs of guide rolls below the mold, a set of power-driven pinch rolls below the guide rolls, and a curved casting guide below the pinch rolls. Before a casting operation begins, a starter bar is inserted upwardly through the pinch rolls and guide rolls to the mold. A stream of molten metal is poured through the mold into contact with the top of the starter bar, which descends through the guide rolls and pinch rolls ahead of the resulting slab. As the slab passes the guide rolls, water sprays are applied to its surface to aid in solidifying it. Initially the leading end of the slab attaches itself to the top of the starter bar, but the starter bar is disconnected as the slab reaches the pinch rolls. At first the pinch rolls restrain descent of the starter bar, but after the slab is part way through the guide rolls, the pinch rolls propel the starter bar and slab. After the starter bar is disconnected, bending rolls within the casting guide bend the slab 90° so that it travels horizontally from there on for further processing. Reference can be made to Foldessy U.S. Pat. No. 3,338,297 for a more complete showing of such a machine, although my invention is not limited to use in this identical machine.

In previous machines of the foregoing type, the guide rolls have all been idlers. Only the pinch rolls are power driven, and the pinch rolls alone are relied on to restrain or propel the descending slab. Consequently there is no control of the vertical forces on the slab until it reaches the pinch rolls. Since only the outer portions of the slab solidify ahead of the pinch rolls, the slab is easily damaged by excessive pressure on its sides or excessive compressive force from above or too much tension.

An object of my invention is to provide an improved guide-roll arrangement in which at least one set of guide rolls are power driven and cooperate with the pinch rolls to control forces on a descending slab.

A further object is to provide an improved guide-roll arrangement in which one or more sets of power-driven rolls bear on a descending slab ahead of the pinch rolls under a controlled pressure and at a controlled torque, thereby regulating the forces on the slab to minimize the possibility of damage, and also to assure that the starter bar is properly disconnected from the slab.

A further object is to provide an improved method of controlling the forces on a descending slab ahead of the pinch rolls.

In the drawings:

FIG. 1 is a diagrammatic side elevational view of a portion of a continuous-casting machine equipped with my improved arrangement of guide rolls;

FIG. 2 is a horizontal section on a larger scale on line II-II of FIG. 1;

FIG. 3 is an elevational view of a portion of the structure from the right of FIG. 2;

FIG. 4 is a vertical section on line IV-IV of FIG. 2; and

FIG. 5 is a vertical section on line V-V of FIG. 2.

FIG. 1 shows a continuous-casting machine which includes an open ended mold 10, four trains of vertically spaced, opposed pairs of idler guide rolls 12, 13, 14 and 15 below the mold, power-driven pinch rolls 16 below the guide rolls, a casting guide 17 below the pinch rolls, and a starter bar 18. The casting guide is equipped with bending rolls 19. These parts can be of a known construction, for example, as shown in the aforementioned Foldessy patent; hence I have not shown them in detail. The machine of course includes other conventional parts which I have not shown, since they are not involved in the present invention. A slab S is shown descending through the machine.

In accordance with my invention, I interpose an upper set of power-driven guide rolls 20 between the two trains of idler guide rolls 12 and 13, and a lower set of power-driven guide rolls 21 between the two trains of idler guide rolls 14 and 15. The two sets of power-driven rolls 20 and 21 are of like construction and similarly mounted; hence I show and describe only the set 20 and their mounting in detail.

As shown in FIGS. 2, 4 and 5, the machine has fixed housing members 22 and 23 at opposite sides. The housing members have horizontal shoulders 24 on which rest opposed frames 25 and 26 for supporting the respective rolls 20. The frames are held in position by keepers 27 and bolts 28 which extend through the housing members and keepers. The two frames and the parts carried by each are of like construction; hence I describe in detail only the frame 25. Frame 25 includes a pair of opposed channels 30, inner and outer transverse bars 31 and 32 rigidly attached at their ends to the channels, and gussets 34 between the end portions of the bars. Preferably the outer transverse bar 32 is bowed outwardly. I slidably mount a pair of opposed bearing chocks 35 in channels 30 and journal the roll 20 in these chocks. Roll 20 has right and left-hand helical grooves 37 extending from its opposite ends toward the middle. I join a drive shaft 38 to one end of roll 20 through a detachable coupling 39.

Two sets of backup rolls 42 of four to each set are journaled in fixtures 43 and bear against roll 20. Each fixture 43 is slidably mounted on a respective pair of studs 44 fixed to the inner transverse bar 31. Pairs of spaced-apart nuts 45 are threadedly engaged with the studs to limit movement of the fixtures. Each fixture has a pair of plungers 46 pivoted thereto and extending through respective openings in bar 31 and a guide 47 fixed to the gusset 34. A leaf spring 48 abuts the ends of the two plungers 46. Cap screws 49 are threadedly engaged with the outer transverse bar 32 and abut the opposite face of the leaf spring. Cover plates 50 span the space between the inner and outer bars 31 and 32 above and below the bars and serve as guides for the spring 48. Thus by turning the cap screws 49 I can initially adjust the pressure with which the backup rolls 42 bear against the roll 20. This pressure remains constant until a further adjustment is made.

A pair of opposed stops 52 are fixed to the inner faces of the housing members 22 and 23 between the channels 30 of the two frames 25 and 26. The channel 30 of frame 25 abuts these stops. I interpose removable spacers 53 of rectangular cross section and removable spacers 54 of angular cross section between the channel of frame 26 and stops 52. By proper selection of spacers, I control the spacing of rolls 20 in accordance with the slab thickness.

To remove the set of rolls 20 from the machine, it is only necessary to uncouple the drive shafts 38 from the roll necks and remove keepers 27 and bolts 28. The two frames 25 and 26 then can slide freely from the housing members 22 and 23. The latter have slots 55 (FIG. 5) through which the roll necks extend in order not to interfere with such removal.

According to my control method, I drive the guide rolls 20 and 21 with a force such that the torque on each set is about 5 to 40 percent of the torque on the pinch rolls 16. The grooves 37 in the surface of the driven guide rolls hold the solidifying slab S. In this manner the two sets of driven guide rolls 20 and 21 and the pinch rolls 16 cooperate to minimize forces in the section of the slab therebetween. This section normally is in considerable tension once the leading end of the slab descends part way through the guide rolls, although ideally it would be free of longitudinal forces (tension or compression). When my invention is employed, the tension is small. This is of particular importance at the time the starter bar 18 is disconnected. My preferred starter bar has a separable chill plate which is mechanically detached from the bar and remains with the slab, as shown or example in my earlier copending application Ser. No. 616,103, filed Feb. 14, 1967 (now U.S. Pat. No. 3,448,789). This type of starter bar can be disconnected properly only when the tensile forces are not excessive. By initially adjusting the cap screws 49, I control the constant pressure with which the driven guide rolls bear against the slab.

While I have shown and described only a single embodiment of my invention, it is apparent that modifications may arise. Therefore, I do not wish to be limited to the disclosure set forth but only by the scope of the appended claims.

I claim:

1. In a continuous-casting machine which includes an open ended mold, trains of vertically spaced opposed pairs of idler guide rolls below said mold, a set of power-driven pinch rolls below said guide rolls, and a curved casting guide below said pinch rolls, the combination therewith of an improved guide roll arrangement comprising at least one opposed pair of power-driven guide rolls among said idler guide rolls, an opposed pair of frames in said machine, bearing chocks mounted in said frames, said power-driven guide rolls being journaled in said chocks, backup rolls mounted in said frame and engaging said power-driven guide rolls, and initially adjustable spring means mounted on said frame for applying a constant pressure to said backup rolls, said power-driven guide rolls being

cooperable with said pinch rolls to control forces on a slab as it travels therebetween.

2. A guide-roll arrangement as defined in claim 1 in which there are two pairs of power-driven guide rolls.

5 3. A guide-roll arrangement as defined in claim 1 in which each of said frames includes inner and outer spaced apart transverse bars, fixtures slidably supported on said inner bar, said backup rolls being journaled in said fixtures, and spring means bearing against said fixtures, and cap screws threadedly 10 engaging said outer bars and bearing against said spring means.

4. A guide-roll arrangement as defined in claim 1 in which said frames are slidably removable from said machine.

5. A guide-roll arrangement as defined in claim 1 in which 15 the surfaces of said power-driven guide rolls have right and left hand helical grooves extending from opposite ends toward the middle.
